UNITED STATES PATENT OFFICE.

WINFRED MUDGE BROOKS, OF EAST ORANGE, NEW JERSEY, ASSIGNOR TO E. J. BROOKS & CO., OF NEW YORK, N. Y., A CORPORATION OF NEW YORK.

BOX-STRAP SEAL.

1,285,608.

Specification of Letters Patent. Patented Nov. 26, 1918.

Application filed May 28, 1918. Serial No. 237,013.

To all whom it may concern:

Be it known that I, WINFRED MUDGE BROOKS, a citizen of the United States of America, and a resident of East Orange, in 5 the State of New Jersey, have invented certain new and useful Improvements in Box-Strap Seals, of which the following is a specification.

The object of this invention is to provide 10 a simple, and efficient seal for metal box straps capable of resisting heavy tension on said straps.

The invention consists in a novel auxiliary sleeve part, of a type similar to that 15 shown is my pending application Serial No. 223,922, the particular construction of which is hereinafter fully described.

One sheet of drawings accompanies this 20 specification as part thereof in which like reference characters denote like parts.

Referring to the drawings Figure 1 shows the sheet metal blank for one type before 25 folding into a sleeve; Fig. 2 shows a top view of Fig. 1 after folding into a sleeve; Fig. 3 shows a top view of this type of seal after sealing. Fig. 4 shows a sheet metal blank for a second type of the improved seal before folding into sleeve form; Fig. 5 is a top view of the second type seal after 30 folding into sleeve form; Fig. 6 shows a top view after sealing and Fig. 7 shows a section taken on the line $m-m$ of Fig. 3. Figs. 8 and 9 are side views of type one and type two seals, respectively, after sealing.

The improved seal is preferably constructed of substantially rigid sheet metal 35 cut in such shape as to be adapted to be folded over on two parallel lines to form a substantially rectangular sleeve, having a top a , parallel sides e' , and bottom e , and 40 adapted to receive the crossed and overlapped ends of a box strap, d . On the lines of the proposed folds, B or U shaped holes are stamped as shown in Figs. 1 and 4 respectively in such manner that upon folding 45 into sleeve form, outwardly pointing lips c c' are formed on each side of the top, the sleeve being cut away from each side and from beneath each of said lips. The metal 50 is stamped and folded into sleeve form at the factory and in this form is ready for use.

In operation the box strap d is passed around the box or bale to be fastened and 55 the ends threaded from opposite ends through the auxiliary sleeve part a and

drawn by any suitable device to the desired tension. The lips c , c' are then depressed by some suitable tool, bending down and interlocking the subjacent portions of 60 the box strap, and thus producing an effective seal. In this sealing operation the fact that the bottom e of the seal has been cut away under each of the prongs enables the prongs to depress and bend down the box 65 strap without cutting or breaking the same and the close engagement of the prong with the depressed portions of the box strap and the adjacent portion of the bottom e will be noted from Fig. 7. With the type of 70 seal shown in Figs. 1, 2, 3, 7, and 8 by modifying the length of the pointed lips c they can be made to project below the bottom of the sleeve and utilized to tack the entire seal securely to the box. The type of seal shown 75 in Figs. 4, 5, 6, and 9, having square prongs or substantially square is particularly adapted for use with bales or burlap covered parcels having no protruding points to snag or tear the cover.

Modifications of the size, shape, and proportions of size, shape and number of the prongs will readily suggest themselves for particular purposes to those skilled in the art.

Having thus fully described my invention, I claim:

1. A seal for box straps comprising the overlapped ends of a box strap, an auxiliary metal sleeve adapted to embrace a portion 90 of their edges and having a top, outwardly directed lateral lips on each side of said top, said sleeve on the sides and beneath said prongs being cut away, said lateral lips being adapted to being depressed and bent 95 down together with the subjacent portions of the box strap substantially as specified.

2. A seal for box straps comprising the overlapped ends of a box strap, an auxiliary sleeve adapted to receive said strap ends 100 provided with a top, outwardly pointing lateral prongs on each side of said top, and adapted to being depressed together with the subjacent portions of the box strap until the points of said prongs point downward and extend below the bottom of the sleeve, substantially as specified.

3. An improved box strap seal consisting of a sleeve adapted to receive the crossed and overlapped ends of a box strap, said 110 sleeve having a top part, outwardly pointing lateral prongs formed in said top part

on each side, said sleeve being cut away from the sides of and from beneath said prongs substantially as and for the purposes specified.

5. An improved box strap seal consisting of a sheet metal sleeve part having a top, sides, and bottom, a plurality of outwardly pointing V-shaped lateral lips on each side

of the top, said sleeve part being cut away at and under said lips to permit of their being depressed downwardly substantially as and for the purposes specified.

WINFRED MUDGE BROOKS.
